DESIGN FOR A RECEPTACLE FOR TOILET COMPOUNDS.

No. 38,183.

Specification for Design.

Patented Aug. 21, 1906.

Application filed June 6, 1906. Serial No. 320,474. Term of patent 14 years.

To all whom it may concern:

Be it known that I, THOMAS W. BALL, a citizen of the United States, residing at Garden City, county of Nassau, and State of New York, have invented a new, original, and ornamental Design for Receptacles for Toilet Compounds, of which the following is a specification, reference being had to the accompanying drawings, forming a part thereof, in which—

Figure 1 is a perspective view of one side of said receptacle, and Fig. 2 is a perspective view of the opposite side thereof.

The design consists of wreaths or ornamental borders representing violets having stems connected or interlaced, substantially as shown.

I claim—

The ornamental design for receptacle for toilet compounds, comprising ornamental borders representing wreaths of violets, substantially as shown and described.

THOMAS W. BALL.
